SWITCH MECHANISM.

1,286,148.

Specification of Letters Patent.

Patented Nov. 26, 1918.

Application filed May 14, 1917. Serial No. 168,428.

To all whom it may concern:

Be it known that I, WILLIAM D. THROOP, a citizen of the United States, residing at Norwich, county of New London, State of Connecticut, have invented an Improvement in Switch Mechanism, of which the following is a specification.

This invention relates to electric switch mechanism and has for its objects to provide a novel switch actuating mechanism of the quick acting type wherein a minimum amount of effort will be required to operate the switch, wherein there will be no dead center, and wherein the parts can be cheaply produced in large quantities and readily assembled.

The invention is illustrated herein in connection with a wall push button switch, but the novel features of the invention are applicable to other types of switches such as sockets, circuit breakers and various other purposes requiring quick opening and closing without liability of sticking on dead center. The invention is also characterized by compactness of construction, whereby particular advantages are obtained where the space is limited, and especially where it is desired to employ shallow wall boxes or other inclosures.

The various features of novelty will be pointed out in connection with the description of the accompanying drawings, in which—

Figure 1 is a side elevation, partly in section of a switch embodying the invention,

Fig. 2 is a side elevation, partly in section,

Fig. 3 is a bottom plan view showing the parts in one position,

Fig. 4 is a similar view showing the parts in the other position,

Fig. 5 is a bottom plan view of the yoke, partly in section,

Fig. 6 is a detail showing the mounting of the button rocker,

Fig. 7 is a detail of one of the contacts, and

Fig. 8 is a sectional view.

1 represents a porcelain or other insulating box carrying line terminals 2, which are connected to conducting bars 3, 3 within the box, and each provided with a stationary switch contact 4. As shown herein, the switch is of the double-pole, double-break type, so that the line terminals and switch

contacts are duplicated as seen in Fig. 2. The contact carrier to which the contact blades 5, 5, are attached, consists of separated members connected by an insulating bridge 6, said members being pivotally mounted on pins 7, 7 which rest at the bottoms of slots 8 in the side walls of the box 1. 9, 9 are insulating washers placed between the switch blades 5 and outside plates 10, 10 and fastened by rivets 11, as seen in Fig. 8, the washers 9 being separated by an insulating washer 12, disposed in the slot 13 of the switch blade 5. By this means, the bridge 6 does not become alive, but is maintained insulated. The pins 7 can be pulled out in order to remove the bridge from the yoke after it is removed from the box.

15 represents the yoke having the usual slots for fastening it to the box at each end, the button guide holes 16, 16 and depending wings 17 having stop lugs 18 for limiting the throw of the switch blades 5 by engaging the bridge 6. The pins 7 pass into holes in the lower portions of the yoke wings 17 so that the bridge 6 and contact blade or blades 5 are thereby connected to the yoke wings 17.

19 is the button rocker which is pivoted to the yoke wings 17 by rivets 20, see Fig. 6, located just above the pins 7. This button rocker is best seen in Figs. 1, 2, 3, and 4 and comprises hooked arms 22 to engage in links 23 of the actuating buttons 24, and a depending arm 25, which engages one end of bow spring 26, in such a manner as to permit the spring to pivot. The other end of the spring is also pivotally connected with the middle of the bridge 6 as at 27. In order to provide positive stops for the buttons, the button rocker 19 is provided with lugs 28 which engage a transverse stop pin 29 carried by the yoke wings 17.

As seen in Fig. 1, the material of the yoke 15 is drawn so as to provide elongated guides for the buttons 24, and the yoke wings 17 the button rocker 19 and the bridge 6 are drawn so as to provide round end elongated bearings 30 so as to reduce friction and increase the life of the switch. These are important features of the invention in connection with the novel features of the operating spring now to be explained.

As will be seen from Figs. 3 and 4, the end of the spring 26 which is connected to the bridge 6 is slightly out of line with the

other end of the spring which is connected to the lug 25 on the button rocker 19, and the function of this is to permit the spring to pivot through practically 180° as the button 5 rocker is actuated, and on an axis which is substantially parallel with the plane of movement of the rocker 19 and the switch members 5. The spring has a continuous pivoting movement both while being compressed, and while expanding, so that on account of this continuous pivotal movement of the spring together with the mounting of its ends so that they can pass each other, there is no point at which a dead center can 10 occur. Moreover, the friction is reduced to a minimum with this mechanism, not only by reason of the specially elongated bearings, above referred to, but because of the pivoting spring which is permitted to follow a natural 15 path and applies its entire energy in throwing the switch blade without loss through unnecessary friction. Upon operation of a button, the switch blade will thus be certainly thrown by the spring, and if the button 20 is not actuated far enough, it is thrown back to its original position as soon as the pressure is relieved. The provision of the stops 18 for the switch blade, independent of the stops 28 for the button rocker, prevents 25 one from interfering with the other, and the latter stops 28 have the further function of positively limiting the movement of the actuator or button rocker and prevent the buttons from becoming jammed. 30

35 The invention is applicable to various other forms of switches than that specifically illustrated herein, and I do not restrict myself to the precise construction shown except as required by the appended claims.

40 What is claimed, is:—

1. An improvement in switch mechanisms comprising an oscillatory switch member, an oscillatory rocker member and a spring connecting said members and mounted to oscillate on an axis parallel with the planes of movement of said members, whereby the switch member will be actuated by movement of the rocker member. 45
2. An improvement in switch mechanisms comprising an oscillatory switch member, an oscillatory rocker member and a spring having its ends attached to said members and positioned to pass each other to permit oscillation of the spring on an axis parallel with the planes of movement of said members, whereby the switch member will be actuated by movement of the rocker member. 50
3. An improvement in switch mechanism comprising an oscillatory switch member, an oscillatory rocker member, and a spring having its ends connected to the respective members, said spring being free to oscillate on an axis parallel with the planes of movement of said members, whereby the switch member 55 will be actuated by movement of the rocker

member, said spring turning continuously on said axis during its compression and expansion in operating said switch member.

4. An improvement in switch mechanism comprising an oscillatory rocker member, 70 and a coiled spring, the axis of the coil being parallel with the axes of said members, the ends of the spring being connected with the respective members, said spring being free to oscillate on an axis parallel with the 75 planes of movement of said members, whereby the switch member will be actuated by movement of the rocker member.

5. An improvement in switch mechanism comprising a yoke, an oscillatory rocker 80 member pivotally supported by the yoke, an oscillatory switch member, and a spring connecting the rocker member and the switch member and mounted to oscillate on an axis parallel with the planes of movement of said 85 members, whereby the switch member will be actuated by movement of the rocker member.

6. An improvement in switch mechanism comprising a yoke, an oscillatory rocker 90 member pivotally supported by the yoke, an oscillatory switch member, a spring connecting the rocker member and the switch member and mounted to oscillate on an axis parallel with the planes of movement of said 95 members, whereby the switch member will be actuated by movement of the rocker member, and means carried by the yoke for limiting movement of the switch member.

7. An improvement in switch mechanism 100 comprising a yoke, an oscillatory rocker member pivotally supported by the yoke, an oscillatory switch member, a spring connecting the rocker member and the switch member and mounted to oscillate on an axis parallel with the planes of movement of said members, whereby the switch member will be actuated by movement of the rocker member, and means carried by said yoke for limiting movement of said rocker member. 110

8. A switch mechanism comprising a member formed of sheet metal having wings each provided with an integral raised boss forming a facial bearing, and the metal extending inwardly and forming a long axial bearing. 115

9. A switch mechanism comprising a yoke having separated bearings, pins each having one end in a bearing of said yoke, a box having supports adapted to receive the other ends of said pins, a switch member pivotally 120 mounted on said pins, a rocker member, and a spring connecting said rocker member and said switch member and mounted to oscillate on an axis parallel with the plane of movement of said rocker member, whereby the 125 switch member will be actuated by movement of the rocker member.

10. A switch mechanism comprising a yoke having separated bearings, pins each having one end in a bearing of said yoke, a box hav- 130

ing supports adapted to receive the other ends of said pins, a switch member pivotally mounted on said pins, a rocker member pivotally supported by said yoke above said 5 pivot pins, and a spring connecting said rocker member and said switch member and mounted to oscillate on an axis parallel with the plane of movement of said rocker member, whereby the switch member will be actuated by movement of the rocker member.

10 11. An electric switch of the character described comprising an oscillatory actuating member, an oscillatory contact carrier, and a spring having its ends engaging said carrier and said actuating member, respectively, at points relatively positioned oblique to the axis of oscillation, whereby the spring will be distorted on its axis by movement of the 15

actuating member, and the torsional movement of the spring thus produced will actuate the carrier.

12. An electric switch of the character described comprising an oscillatory actuating member, an oscillatory contact carrier provided with separated blade-carrying members connected by a bridge piece, and a spring having its ends engaging said carrier and said actuating member, respectively, at points relatively positioned oblique to the axis of oscillation, whereby the spring will be distorted on its axis by movement of the actuating member and the torsional movement of the spring thus produced will actuate the carrier.

20 25 30 35 In testimony whereof I affix my signature.

WILLIAM D. THROOP.
